DESIGN FOR A COMBINED CLOCK AND RADIO RECEIVER

Robert Henry Fisher, New York, N. Y., assignor to
Whiting Holding Company, Minneapolis, Minn.,
a corporation of Minnesota

Application September 18, 1936, Serial No. 64,911

Term of patent 7 years

To all whom it may concern:

Be it known, that I, Robert Henry Fisher, a citizen of the United States, residing at New York city, the Bronx, and State of New York, have invented a new, original, and ornamental Design for a Combined Clock and Radio Receiver, of which the following is a specification, reference being had to the accompanying drawing, forming a part thereof, wherein

Fig. 1 is a front perspective view of a combined clock and radio receiver with the doors thereof closed showing my new design, and

Fig. 2 is a perspective view of the same with the doors thereof open.

I claim:

The ornamental design for a combined clock and radio receiver, substantially as shown.

ROBERT HENRY FISHER.
